UNITED STATES PATENT OFFICE.

THOMAS I. LUDWIG, OF JACKSON, MICHIGAN.

CORN-HUSKER.

977,205.

Specification of Letters Patent. Patented Nov. 29, 1910.

Application filed November 8, 1909. Serial No. 526,835.

To all whom it may concern:

Be it known that I, THOMAS I. LUDWIG, a citizen of the United States, residing at Jackson, in the county of Jackson and State 5 of Michigan, have invented a new and useful Corn-Husker, of which the following is a specification.

This invention relates to corn huskers of that type such as disclosed, for example, in 10 an application for U. S. Letters Patent filed by me on June 11, 1909, Serial No. 501,625. In a device of this class in which the metal parts are formed of stiff wire, it has been found that more or less play occurs between 15 the hook member of the husker and the adjoining supporting loop thereof, during the husking operation, this relative movement resulting in the rapid wearing of the leather attaching devices which are wrapped about 20 or otherwise connected to the metal portions of the husker.

One of the objects of the present invention is to provide a husker of this character in which the hooked element is fixed relative to 25 the adjoining portion of the structure, this being effected in a variety of ways.

Another object is to render devices of this character more durable without adding to the cost thereof, and to remove all objectionable projections and the like that tend to 30 bite into or otherwise injure the flexible attaching devices.

With these and other objects in view the invention consists of certain novel details of 35 construction and combinations of parts hereinafter more fully described and pointed out in the claims.

In the accompanying drawings the preferred forms of the invention have been 40 shown.

In said drawings, Figure 1 is a perspective view of a husker constructed in accordance with the present invention. Fig. 2 is a perspective view of the metal portion of a 45 modified form of husker. Fig. 3 is a similar view showing another form of husker. Fig. 4 is a perspective view of the metal portions of another form of corn husker. Fig. 5 is a view showing, in detail, another modification. Fig. 6 is a perspective view of the metal portion of a husker in which the hooked member is formed of a piece separate from the remaining portion of the husker.

5 Referring to the figures by characters of

reference 1 designates an elongated, substantially elliptical eye formed preferably of stiff wire and one of the terminals of the wire is extended laterally from the eye to form a loop 2 terminating in an eye 3 which extends 60 around the longest side of the loop and is thus held in fixed relation thereto, the other end portion of the wire being extended through the eye 3 as shown at 4 and forming a stem which terminates in a husking 65 hook 5, this hook bearing upon the crown portion of the loop. The eye 3 extends tightly around the long arm of the loop 2 and around the end portion 4 and serves to bind the parts tightly together so that there 70 is no independent movement of the parts during the husking operation.

The means utilized for attaching the metal portion of the husker to the hand is similar to that which has been described in my application hereinbefore mentioned. The flexible wrist strap 6 is wrapped about the loop 2 and close to the eye 1 this wrist strap being then threaded through the eye and held thereto by means of thong 7 which is threaded through the strap and around the eye as shown. The thong extends through the hooked ends 8 of a connecting wire 9 and thence through a slit 10 formed in the wrist strap after which the thong is fastened to 80 the eye and is secured to the wrist strap close to the buckle 11. The connecting wire 9 extends under the loop 2 and over the stem 4, the same being held frictionally by the looped stem so as to maintain a substantially fixed position with relation thereto. A wire 12 may be extended from one of the hooks of the connecting wire, this last mentioned wire 12 being provided with an eye 13 through which the thong 7 extends. This 90 wire serves to hold the thong normally spread away from the metal portion of the husker so as to permit the thumb to be readily inserted between the thong and the loop 2.

Instead of wrapping the ends of the looped portion of the wire transversely of said loop as shown in Fig. 1, said wire can be brought up to the eye 14 and wrapped therearound as indicated at 15 in Fig. 2 and, 105 if preferred, said end of the wire can be slit longitudinally, as shown at 16 in Fig. 3 and the two end portions thus produced can be wrapped about the eye 17 and the stem 18. In view of the fact that under some condi- 110

tions these wrapped or looped portions of the wire will become objectionable because of their bulky nature, the end of the looped portion of the wire can be brought against the eye 19 and welded or soldered thereto as shown at 20 in Fig. 5 or, if preferred, that end of the loop 21 adjoining the eye 22 can be closed with solder as shown at 23, this solder also serving to attach the end of the loop portion of the wire to the eye. This arrangement has been shown in Fig. 4. In both of the constructions shown in Figs. 3 and 4 the hook is designed to be fastened to the crown portion of the loop either by welding or soldering it thereto.

In Fig. 6 a structure has been shown wherein the eye 24 is provided with parallel arms 25 terminating in eyes 26. The hook 27 is formed at one end of the stem 28 which extends between the arms 25 and is then wrapped about the arms of stem as shown at 29, these wrapped portions serving to bind the stem and arms tightly together so as to positively prevent any independent movement thereof.

It will be noted that in all of the forms herein described it is impossible for the hook and loop or eye to have any independent movement. In every instance the ends of the wire are so disposed as to prevent injury to the straps or other fastening devices used and where elongated loops are employed for supporting the hooks, the ends of the wires constituting the loops are positively secured against movement.

Various changes can of course be made in the construction and arrangement of the various parts without departing from the spirit or sacrificing any of the advantages of the invention.

What is claimed is:—

1. A corn husker including a wire bent to form an eye and an outstanding portion, said outstanding portion having its terminal wrapped in engagement with an intermediate portion of the wire, and a stem integral with the eye and extending within and bearing upon the outstanding portion, said stem having a hook at the free end thereof, and the point of which is directed toward the eye.

2. A corn husker formed of a single length of wire bent into an eye and an outstanding loop, one end of said wire being attached to an intermediate portion thereof and the other end of the wire being extended outwardly to constitute a hook the point of which is directed toward the eye, said hook being disposed in a plane perpendicular to the plane occupied by the loop.

3. A corn husker including a wire eye having an integral outstanding portion having opposite sides thereof fixed relatively to the eye, a stem within and fixed relatively to said outstanding portion, and a husking hook formed by one end of the stem.

4. A corn husker including an eye having an integral outstanding portion, opposite sides of said portion being fixed relatively to the eye, a stem within and fixed relatively to said portion, and an outstanding husking hook formed by one end of the stem.

In testimony that I claim the foregoing as my own, I have hereto affixed my signature in the presence of two witnesses.

THOMAS I. LUDWIG.
